KNOCKDOWN BOX

Herbert C. Skell, Baldwin, N. Y., assignor to The
Hinde & Dauch Paper Company, Sandusky,
Ohio, a corporation of Ohio

Application August 4, 1943, Serial No. 497,328

2 Claims. (Cl. 229—23)

This invention relates to boxes of the knock-down type made of relatively stiff sheet material such as corrugated paper board divided into panels and flaps by scored, creased or otherwise weakened fold lines which hingedly connect the panels and flaps so that flat pieces of the sheet material may be folded to form the box.

It is an object of the invention to provide a box that possesses superior rigidity and strength and that can be quickly and easily assembled.

A further object of the invention is to provide a knockdown box composed of two pieces of sheet material that can be quickly and easily assembled and folded into interlocking relation and which can be quickly and easily unfolded and laid flat for storage or shipment.

A further object of the invention is to provide a knockdown box which has relatively rigid walls releasably locked together and held in upright position by means of interengaging flaps carried by the walls.

With the above and other objects in view, the invention may be the knockdown box as illustrated in the accompanying drawings hereinabove described and particularly set forth in the claims, together with such variations and modifications thereof as will be apparent to one skilled in the art to which the invention pertains.

Reference should be had to the accompanying drawings forming a part of this specification in which:

Figure 1 is a perspective view of a box embodying the invention;

Figure 2 is a perspective view showing the box partially assembled;

Figure 3 is a section taken on the line indicated at 3—3 in Figure 1;

Figure 4 is a section taken on the line indicated at 4—4 in Figure 1;

Figure 5 is a plan view of one of the two foldable pieces of sheet material employed in making the box; and

Figure 6 is a plan view of the other foldable piece of sheet material that interlocks with the first to complete the box.

As shown in the accompanying drawings, the box of the present invention is composed of two pieces of sheet material such as shown in Figures 5 and 6 of the drawings, one of which forms the front wall, bottom, back wall and lid, and the other of which completes the box and interlocks with the first piece to position the walls of the box and fasten them together.

The piece of sheet material forming the front, bottom and rear walls and the lid is shown in

5 Figure 5 of the drawings and this piece has a central panel 1 adapted to form the bottom of the box and an adjoining panel 2 connected with the panel 1 by a fold line 3 and adapted to form the rear wall of the box. A panel 4 is joined to the panel 1 by a fold line 5 and is adapted to the front wall of the box. The rear wall panel 2 is provided with end flaps 6 hingedly connected thereto by fold lines 7 and the front wall panel 4 is provided with end flaps 8 hingedly connected thereto by fold lines 9. The panels 2 and 4 are adapted to be folded up about the fold lines 3 and 5 to positions at right angles to the bottom panel 1 and the width of flaps 6 and 8 is substantially one-half the width of the bottom 1 so that the flaps 6 and 8 are adapted to abut edge to edge when swung to positions at right angles to the panels 2 and 4 after the latter panels have been moved to upright position. The front wall panel 10 has a flap 10 connected to its top edge by a double fold line 11 and a longitudinal slot 12 is formed in the fold line 11 intermediate the ends thereof. The flap 10 is adapted to be folded inwardly against the inner face of the panel 1 when the box is assembled so that the slot 12 opens to the top edge of the front wall. A lid 13 is hingedly connected to the top edge of the back panel 2 by means of a fold line 14 and the lid 13 has a hinged tongue 15 at its free edge 16 which is connected thereto by a fold line 16, the tongue 15 being adapted to enter the slot 12 and to be frictionally held between the front panel 4 and flap 10 to releasably retain the lid in closed position.

35 The second piece of material used in forming the box is shown in Figure 6 and has a central or bottom panel 17 that is adapted to rest upon and cover the bottom panel 1 of the piece first described. End wall panels 18 are hingedly connected to the panel 17 by fold lines 19 and each of the panels 18 has a flap connected thereto by a double fold line 21.

40 In assembling the box, the piece of sheet material shown in Figure 6 of the drawings is placed upon the piece of material shown in Figure 5 at right angles thereto with the panel 17 lying upon and covering the panel 1. The front and rear wall panels 2 and 4 are then swung upwardly to vertical position and the flaps 6 and 8 are folded inwardly to positions at right angles to the panels 2 and 4 to bring them into the same plane at each end of the box with their free edges in engagement as shown in Figure 2. The end wall panels 18 are then folded upwardly against the exterior faces of the flaps 6 and 8 and the flaps

20 are folded downwardly against the interior faces of the flaps 6 and 8 after which the flap 10 is folded inwardly against the inner face of the front wall panel 4.

As shown in Figure 5, the bottom edges of the flaps 6 and 8 are offset from the fold lines 3 and 5 a distance substantially equal to the thickness of the sheet material, so that when the panels 2 and 4 are folded to upright position, the lower edges of the flaps are spaced above the bottom 1 10 enough to permit them to be folded inwardly over the top surface of the panel 17. The side edges of the front wall flap 10 are offset inwardly from the fold lines 9 substantially the thickness of the sheet material to make the width of the 15 flap such that it is adapted to fit snugly between the flaps 20 when it is swung inwardly against the inner face of the front wall panel 4. The edges of the flap 10 engage with the inner faces of the two flaps 20 to hold these flaps tightly 20 against the interior faces of the flaps 6 and 8, the frictional engagement between edges of flaps 10 and the faces of the flaps 20 also serving to hold the flaps 10 in vertical position.

The flap 10 thus serves as a locking flap to retain the upright walls of the box in operative position. While the flaps 10 and 20 will coact as above described if made shorter than herein shown, it is preferred that these flaps be full depth flaps having their free edges closely adjacent the upper bottom panel 17. If desired the flaps may frictionally engage the panel 17 to assist in retaining them in vertical position. The flaps 6 and 8 are preferably of a height to fit snugly between the bottom panel 17 and the interiors of the double folds 21 at the tops of the end walls so that the front and rear walls are firmly held by the end walls.

The lid 13 is preferably of a size to lie flush with the outer surfaces of the front and end walls when in its closed position resting upon the doubled edges of said front and end walls and is held in closed position by frictional engagement of its tongue 15 with the front panel 4 and flaps 10 of the front wall.

The box can be readily knocked down by first moving the flap 10 upwardly and outwardly and then opening the flaps 20, after which the two pieces of sheet material may be folded flat.

It will be apparent that the present invention provides a box having strong and relatively rigid walls that can be quickly assembled or knocked down and that requires no separate fastening elements or special locking tabs to retain it in assembled operative position.

It will also be apparent that various modifications of the construction herein shown and de-

scribed can be made without departing from the spirit of the invention as defined in the appended claims.

What I claim is:

1. A knock down box composed of two pieces of relatively stiff paperboard, one of said pieces comprising a bottom panel, front and back wall panels having their bottom edges hingedly connected by fold lines to opposite side edges of the bottom panel, an inturned flap hingedly connected by a fold line to the top edge of the front wall panel, the latter fold line having a slot intermediate the ends thereof, a lid panel hingedly connected by a fold line to the top edge of said back panel and a tongue of a width to enter said slot hingedly connected to the free edge of said lid panel, said front and back panels having hinged end flaps adapted to be positioned in a plane at right angles to said front and back panels, the other of said pieces having a central panel corresponding to the bottom wall panel of the first piece and adapted to overlie the same, end wall forming panels hingedly connected at their bottom edges by fold lines to the opposite ends of said central panel and inturned flaps hingedly connected to the top edges of said end wall panels, said inturned flaps extending substantially the full depth of the box with the front wall flap engaging the interior faces of said end wall flaps, said end flaps being interposed between the end wall panels and flaps with their top edges contiguous to the interior of the top edge folds of the end walls and their bottom edges contiguous to said central panel.

2. A knockdown box composed of two pieces of sheet material, each comprising relatively rigid panels and flaps hingedly connected by fold lines, one of said pieces having bottom, front and back wall panels, the other of said pieces having a central panel resting upon the bottom panel of the first piece and end wall panels, said front and back wall panels having end flaps engaging the interior faces of said end wall panels with their bottom edges closely overlying said central panel, 45 said end wall panels having flaps connected to their top edges and folded inwardly over the top edges of said end flaps, said front wall panel having an inturned flap connected thereto by a fold line at its top edge, the end wall flaps overlying 50 the inner faces of said end flaps and the front wall flap being interposed between the end wall flaps and engaging the same to hold them against said end flaps, the fold line at the top edge of the front wall having a slot therein, and a lid 55 hinged to the back wall and provided with a tongue adapted to enter said slot.

HERBERT C. SKELL.
